VARIABLE HIGH-VOLTAGE ELECTRICAL
CONDENSER

Robert P. Guttermann, Silver Spring, Md., assignor
to Engineering Research Associates, Inc., St.
Paul, Minn., a corporation of Minnesota

Application June 15, 1949, Serial No. 99,203

8 Claims. (Cl. 175—41.5)

1

This invention relates to electrical condensers, such as those generally used in radio, television, or similar electrical circuits.

More particularly, this invention relates to variable electrical condensers which are capable of withstanding high voltages. The purpose of such variable high voltage condensers is generally to provide a capacity whose value can be regulated at will and which is capable of being used in circuits having a high impressed voltage, either D. C. or high frequency. Condensers of this type find wide application in the output loading circuits of almost any radio transmitter having an output greater than a few watts. Heretofore, such high voltage variable condensers have been available in a wide variety of physical sizes and electrical capacities, but none of those currently available combine a high electrical rating with a small physical size.

Heretofore, variable air condensers have generally been fabricated from a plurality of interleaved electrodes, so arranged that the metallic sheets constituting the electrodes could be moved together or apart by the actuating means. In each case, the dielectric was usually air, although sometimes compressed gases and even liquids have been used satisfactorily. However, the dielectric constant of all gases, and of all liquids which are otherwise satisfactory, is very low; hence, a large amount of dielectric must be employed to obtain a given capacity rating. Attempts have also been made to introduce solid dielectrics between the electrodes, but the results have not proven generally satisfactory. Difficulty has been encountered as a result of the mechanical wear arising from the relative movement of electrodes against the dielectric, which movement must necessarily take place in a variable condenser. This wearing action may cause particles of the metal electrodes to become embedded in the dielectric, or may cause the dielectric to score the electrodes, or may create such a diminution in the dimensions of one or the other or both, that the capacity at a given dial setting is no longer constant. Particularly in the case of high voltage condensers, the above wearing action is very serious, since corona effects may be stimulated, resulting in highly erratic operation and eventual total destruction of the unit. Furthermore, in the case of precision condensers (such as are now required for use in transmitters which must operate in narrow frequency bands and, therefore, hold to a precise tuning), both the effect of abrading of the electrode by the dielectric and the effect of metallic impregnation of the dielectric

2

is extremely serious. The obvious method for overcoming this difficulty is to provide an intervening layer of air between the dielectric and the relative moving electrode. However, this, in turn, raises other difficulties, particularly insofar as this scheme requires the use of mechanically precise bearings in order to bring the intervening air layer down to dimensions which are practical since, obviously, if the intervening air layer is not kept small, the result will degenerate to what is essentially an ordinary air-dielectric condenser.

Other schemes for overcoming the above objections have similarly been proposed. A typical example is Patent No. 2,219,921, which shows a variable condenser in which the dielectric is split, so that the relative movement takes place between lapped halves of the dielectric rather than between the dielectric and electrode. While this may overcome the difficulties arising from the sliding of dielectric against electrode, nevertheless, such a condenser is costly to manufacture, is large and bulky for a given capacity rating and will vary so much that it cannot qualify generally as a precision component.

It is a principal object of this invention to provide a variable high voltage electrical condenser of simple construction which shall be considerably smaller than existing devices of this type of equivalent electrical rating.

Further objects of this invention are to provide:

- (1) Variable high voltage condensers which shall be useful in connection with the present tendency in the entire radio art toward miniaturization, both of components and complete assembly.

- (2) Variable high voltage condensers which shall be easier and cheaper to manufacture than existing devices of equivalent electrical rating.

- (3) Variable high voltage condensers which will withstand the adverse effects of operation at low atmospheric pressure, such as that encountered in aircraft transmitters when the aircraft is operating at high altitudes.

- (4) Condensers having a structure which allows complete electrostatic shielding.

- (5) High voltage condensers in which the defects and limitations associated with the use of air gaps as dielectric elements are eliminated at the same time that abrasive wear of moving components and the attendant instability in electrical characteristics of the condensers is not introduced.

- (6) High voltage condensers having relatively moving parts constructed so that an electrically

precise structure is provided without recourse to precision bearings or similar units generally employed for this purpose.

Still further objectives and the entire scope of applicability of the present invention will become apparent from the detailed description given hereinafter; it should be understood, however, that the detailed description, while indicating a preferred embodiment of the invention, is given by way of illustration only, since various changes and modifications within the spirit and scope of the invention will become apparent to those skilled in the art from this detailed description.

A more complete understanding of the structure involved with this invention may be had by reference to the accompanying drawing.

It will be understood that this is a preferred arrangement of parts, but other arrangements, including other means for adjusting the moving parts, can be employed. The novel features of this invention do not reside solely in the particular layout of parts in this illustration of a specialized 2-section condenser.

In the drawings:

Figure 1 is a longitudinal cross-sectional view of a 2-section, variable high voltage condenser incorporating the features of this invention;

Figure 2 is a cross-sectional view along line 2-2 of Figure 1;

Figures 3 and 4 are electrical diagrams of the equivalent circuit.

Referring first to Figure 1, the 2-section condenser has two stator electrodes 10 and 10' which are insulated from the case and from each other by mounting means 20, 21, 31', 22 and 22', hereinafter described in greater detail. The movable electrode consists of the single nickel block 36 which is electrically common to both sections and which is also grounded to the case 40 by reason of the conductivity of its actuating means, which actuating means comprise preliminarily the outside threaded shaft 50 and associated fittings 51 and 52. Stated otherwise, this condenser has two electrical terminals 21 and 11', each representing one side of one of two variable condensers, the other side of which is common to both units and grounded. The latter grounded element furthermore acts as an electrostatic shield for the entire unit.

The electrodes 10 and 36 constitute opposed electrostatic electrodes of the one section of the condenser, while the dielectric elements 11, 12, 13 and 31 constitute a composite dielectric of co-operating parts, the part 11 having no inherently variable feature, while the parts 12, 13 and 31 are capable of relative movement one to the other. The same is true of the other section of the condenser. The importance of this is more fully explained hereinafter in connection with Figures 3 and 4 of the drawing.

The electrode 10 of the stationary capacitive element is shown conveniently as a length of hollow cylindrical tube. This electrode is permanently and coaxially embedded in a ceramic cylinder 11 which is composed of a ceramic having a high dielectric constant and a high dielectric strength. An example of such a ceramic is a mixture of titanium dioxide, and silica, which is available with a dielectric constant of 100 and with excellent dissipation factor and high dielectric strength. The choice of this or some other suitable material is dictated by the requirements of the particular condenser which is to be built, and this selection, which may be done by anyone

skilled in the art, is not the subject matter of this invention. However, as far as is known to the inventor, there is no material electrically suitable for the cylinder 11 which can be rubbed in contact with a metallic electrode without adversely affecting either the metallic surface or the cylinder 11 or both, thereby eventually destroying the condenser as a whole. In this invention, the outer surface of the cylinder 11 and the mating surface of the moving metallic block 30 are treated so as to produce, on the mating surfaces, an entirely different substance which is capable of frictionally operating against itself indefinitely without any deleterious effects. This treatment, described below in greater detail, results in the achievement of the objectives outlined previously.

The cylinder 11 may be any ceramic or other dielectric material capable of withstanding temperatures of at least 1000° F. This is first given a coating of nickel on at least the external cylindrical surface. While there are many ways of accomplishing this nickel plating, such as by electro deposition, electrophoresis, chemical deposition, metallic evaporation techniques, or cathode sputtering, the preferred method is to use a process known as "gas plating" described in considerable detail in U. S. Letters Patent No. 2,332,309 and No. 2,344,138, and British Patent No. 487,854 of June 1938. It is enough for the purpose of describing the present invention to state only that the process consists of immersing the ceramic cylinder 11, previously heated to a temperature of about 350° F., in an atmosphere of nickel carbonyl. At this temperature, the gaseous $\text{Ni}(\text{CO})_4$ decomposes into carbon monoxide and pure nickel, the latter being deposited on the surface of the heated cylinder 11. The decomposition of nickel carbonyl under these conditions has been known since about 1890 and the application of these phenomena for plating purposes has been successfully exploited for a number of years.

After the nickel plating has been accomplished, the entire cylinder 11 is heated in an oxidizing atmosphere so as to convert the coating 12 entirely into nickel oxide. The process for doing this is described at length in my previous application for U. S. Letters Patent, Serial No. 49,022, filed September 13, 1948, now abandoned. In brief, the process consists in heating the nickel to a temperature of 1000° to 2500° F. in a current of gas containing oxygen, and subsequently allowing the nickel to cool. The heating, timing, and cooling must be under controlled conditions, the details of which will be found in the aforementioned application Serial No. 49,022. In general, the process as previously disclosed resulted in the formation of a tightly adherent layer (comprised of a mixture of the various oxides of nickel) over a base of the original metallic nickel. In the present invention, however, the entire layer of nickel previously deposited by the gas plating process is converted to a mixture of nickel oxides by the high temperature oxidation process. Stated otherwise, the entire layer 12 is converted to nickel oxide, there remaining no metallic nickel in this layer upon completion of the oxidation process. Obviously, the times and conditions of the gas plating process must be properly correlated with the times and conditions of the oxidation process in order that this conversion may be effected completely. While it is not possible to define explicitly the precise times and conditions required to achieve this result, previous

experiments indicate that the layer 12, when in its metallic state prior to conversion to the oxide, should preferably have a thickness of the order of magnitude of .0002" to .002".

It will be noted that the gas plating process is equally applicable to other metals having metastable carbonyls, such as iron, cobalt, chromium, and the like, although nickel is presently the preferred material for carrying out my invention, because of the hereinafter described desirable properties of its oxides.

In a similar manner, the cylinder 11' is provided with a coating 12'.

The other electrode is composed of the nickel block 30 which is fabricated to a shape best illustrated in Figure 2. This block has two holes which are very slightly larger in diameter (about .0005") than the completely processed cylinders 11 and 11'. This block is first completely fabricated to the desired dimensions, including not only the two holes previously mentioned but also including facilities for actuating it (which facilities may consist of the threaded portion 32 for moving it laterally and also the outer surfaces 33, 34, 35 and 36, of which two or more may be used to guide the block 30 and prevent it from twisting in the case 40 when the shaft 50 is rotated). After fabrication, this entire block is heated to form an oxide on at least the interior surface 31 and 31' of the two holes. This oxidizing process is also carried out in accordance with my previously mentioned application for U. S. Letters Patent, Serial No. 49,022. The oxide will tend to form all over the block 30, although it is required only on the interior cylindrical surface 31 and 31'. It may be removed elsewhere if this is desired and, in particular, it may be removed from the interior threaded surface 32 in order to make the block 30 electrically conductive to the shaft 50, although other means for bringing out the connection to movable block 30 (such as by a flexible lead) are obvious.

Electrode 30 may also be fabricated of some base metal which is subsequently nickel-plated and then treated as described above.

Summarizing the foregoing steps, it will be seen that both the cylinder 11 and the moving block 30 are now provided, at their mating surfaces, with a coating consisting of a tightly adherent layer of the various oxides of nickel. In more detail, the outer surface 12 of cylinder 11 and the inner surface 31 of moving block 30 are composed of a mixture of the oxides of nickel. This is also true of mating surfaces 12' and 31'. It will be found that such an arrangement has some unusual properties and gives rise to some results which might not be expected, were it not for my discovery of these properties in the course of experimenting with this material. First, the cylinder 11 engages with the block 30 in such a way as to provide a very freely running fit, even when the clearance between the two units is as little as .0003". Ordinarily, a fit as close as this, between two metallic surfaces or between a metal and a ceramic or glass, would be classified as a "push" or "force" fit and obviously unsuitable for this application. But, when mating surfaces of oxide, previously described, are run together with such small clearance, there is in effect provided a bearing which may be run dry and which will exhibit the properties of a jewel bearing.

The unusual properties of a nickel oxide mixture itself are set forth in detail in my previously mentioned application, Serial No. 49,022.

The unusual properties of this oxide-on-oxide

bearing are further disclosed in my application for U. S. Letters Patent, Serial No. 83,494, filed March 25, 1949. The latter application discloses a condenser fabricated from two metallic electrodes (preferably of nickel) which are subsequently oxidized at their mating surfaces. In the present application, only one of the mating parts 30 is fabricated from metal and subsequently oxidized, whereas the other 11 is fabricated from a non-metal (such as the aforementioned titanium dioxide and silica ceramic) which is then metal-plated, and this metal-plating is then oxidized in its entirety, so that the plated layer is completely converted to a non-conducting layer of oxide and so that no metallic material remains.

Returning again to Figure 1, it will be noted that the small clearance between block 30 and cylinders 11 and 11' will require that the latter be mounted in such a way, that no conflict will result between the position of these cylinders as defined by the mounting means and the position as defined by the mating block 30, when it is in various stages of engagement with the blocks 11 and 11'. In brief, cylinders 11 and 11' should be "floated" within the block 30 in such a way that they can yield so as to conform to any minor eccentricities or wobble in the actuating means 32 and 50. If this is not done, then obviously the entire mechanism must either be made to prohibitively close dimensional tolerances or else, the entire unit will bind. It is possible to so suspend the cylinders 11 and 11' that they are rigidly positioned in the axial direction, while still being yieldably positioned in the orthogonal or radial direction.

In the present invention, this is accomplished by providing a cantilever wire 21, preferably of spring steel, beryllium-copper, or Phosphor bronze, or other suitable metal, which engages with the far end of sleeve-electrode 10 by means of a metallic element 22 (which may be a block of solder poured into the internal cavity of sleeve 10 approximately to the depth indicated in the figure and then allowed to harden). A generous clearance is provided between the internal dimension of sleeve 10 and the external dimension of cantilever wire 21, so that the former may wobble a considerable distance in all directions, except axially, at either end without permitting the internal surface of 10 to contact the external surface of 21. This type of mount functions smoothly and efficiently in connection with the rest of the condenser mechanism; particularly it cooperates well with the close fit between surfaces 12 and 31. A similar arrangement 21' and 22' is provided for the other electrode 10'. Thus the end fitting plate 20 may be manufactured to ordinary machine tolerances insofar as the positions of 21 and 21' are concerned; furthermore, this insulating end plate may be retained in the case 40 simply by crimping the end thereof as shown at 41.

Considering now the resulting electrical condenser, each section may be regarded as a circuit consisting of two condensers effectively connected in series. The first condenser comprises the metallic electrode 10 and the ceramic 11, but the other electrode of this condenser does not actually exist as such, and may be referred to as a phantom electrode. The second condenser consists of the electrode 30 and a dielectric comprising the two layers of nickel oxide 31 and 12 (together with a negligible airgap 13 therebetween) and the same phantom electrode for the other side. This equivalent circuit is shown in Figure 3.

Equivalent condenser I is effectively the high-voltage section, and across it appears virtually all of the voltage drop between working electrodes 10 and 30. Condenser II has relatively little effect on the equivalent electrical circuit since it is of a much larger capacity than condenser I. As is known, a series circuit consisting of a large and a small capacitor will exhibit a capacity very nearly equal to that of the small capacitor. However, it is the capacitor II which is responsible for providing the mechanically variable characteristic of this condenser. Again because of fundamental considerations of the equivalent circuit, very little of the impressed voltage from 10 to 30 appears across the dielectric composed of 12, 13, and 31. This is done deliberately because the latter composite dielectric is not capable of withstanding very high voltages, being limited to a maximum of under 1000 volts. Thus equivalent condensers I and II cooperate in such a manner that I provides the high voltage condenser which is to be varied, whereas II provides the means of accomplishing this variation, the two together cooperating so as to provide a variable condenser which may be operated above, say, 10,000 volts. In varying the condenser, it must be remembered that electrode 30 and the phantom electrode must be moved together relative to electrode 10, as no variation could occur if the phantom electrode remains stationary.

Returning now to Figure 1, it will be seen that the device illustrated fits this requirement, provided of course, that the layer 12 is totally converted to the dielectric consisting of a mixture of the oxides of nickel and that no metallic nickel is allowed to remain in this layer. Thus, the equivalent circuit may be further reduced to that shown in Figure 4 which schematically illustrates condensers I and II effectively connected in series and ganged together in such a manner, that they vary together.

The above description of the circuit is presented solely for the purpose of exposition and illustration of what is accomplished by my invention, in order that this may be more readily comprehended by the reader. The invention itself, however, is not to be construed as narrowly limited to the mere connection of two condensers in series (this being known in the art), but rather as defined by the scope of the claims which will be appended below.

Another feature which may be incorporated in this invention is the provision of means for overcoming thermal variations in the capacity of the unit. As a first approximation, the condenser may be made by fabricating the case 40 and the shaft 50 of the same material, e. g., nickel, as the block 30. Further improvement may be had by a judicious choice of these materials, together with the choice of material for the cantilever electrode 21 and 21'. Likewise, certain elements, such as the closed end 42 of case 40, may be fabricated of bimetallic elements. In the design of these temperature-compensating means, considerable advantage may be taken of the fact that cylinder 11 has a very low coefficient of thermal expansion, whereas block 30 has quite a large such coefficient; although in both cases, the layer of nickel oxide (12 and 31) is so tightly adherent of the underlying material, that there is no danger of it separating therefrom.

As will be apparent from the discussion given above, nickel is the preferred metal from which the important metallic portions, elements 10 and 30, of these new condensers should be fabricated

and also the metal from which the oxide coatings 12 and 31 should be formed. However, other metals may be used in the formation of the tubes 10 and the element 30, such as silver, brass, aluminum, or any other similar inert, electrically conducting metal. Also other metals besides nickel may be used to form the oxide coatings 12 and 31, including the metals: rhodium, iridium, osmium, ruthenium, cobalt, molybdenum, and chromium.

While the disclose of the present invention is directed toward high voltage transmitter condensers, and while furthermore their use in transmitters is probably the most likely application of these condensers, the application of these high voltage variable condensers is not limited to this field alone.

I claim:

1. A high voltage variable condenser comprising a housing, a pair of capacitive elements carried by said housing, one of said elements being a high voltage element of tubular shape comprising an internal metal tube, a surrounding tubular body of ceramic material carried by said metal tube and an adherent layer consisting of a stable metal oxide overlying said ceramic material, the second element being a low voltage element comprising a metallic member having a tubular opening therein of a shape corresponding to said high voltage element, but slightly larger in size, whereby said high voltage element may slide axially within said opening, said opening having a surface formed of a layer of stable metal oxide and means carried by said housing for moving said elements relative to one another.

2. A condenser as claimed in claim 1, wherein said high voltage element is mounted upon one end of a compliant cantilever wire which extends axially within said element, said wire being rigidly fastened at the other end to a portion of said housing.

3. A condenser as claimed in claim 1, wherein said ceramic body is greater in depth than the combined depth of said stable metal oxide coatings and the air gap between said coatings.

4. A condenser as claimed in claim 1, wherein said element moving means comprises an outside threaded member carried by said housing so as to permit free rotation without longitudinal motion, said outside threaded member being threaded into an inside threaded section on said low voltage element.

5. A variable condenser as claimed in claim 1, wherein one of said elements is mounted on means for accurately positioning the elements rigidly in the direction of said motion responsible for the variation in electrostatic capacity while yieldably positioning the element in all other directions, whereby a free-running fit between said relatively movable elements is provided.

6. A variable condenser as claimed in claim 1, in which said second element comprises a pair of layers of an oxide of a metal selected from the group consisting of rhodium, iridium, osmium, ruthenium, cobalt, molybdenum, chromium and nickel, said layers being capable of relative movement, one past the other, while in contact with each other.

7. A high voltage variable condenser comprising a box-like housing, two high voltage capacitive elements comprising an inside metal tube, a surrounding ceramic tubular body carried by said metal tube and a layer of stable metal oxide overlying said ceramic body, each of said elements being carried within said housing substantially

parallel to one another upon a wire which extends centrally down said inside metal tube with the tube being fastened to one end of the wire and the other end of the wire being rigidly supported by said housing, a low voltage capacitive element slidably carried within said housing comprising a block-like metallic member having two tubular openings therethrough corresponding in shape to said high voltage elements into which high voltage elements extend, an inside threaded section in said low voltage element, an outside threaded member fixed against longitudinal motion while being allowed to rotate in an opening in said housing, said outside threaded member being threaded into said inside threaded opening, whereby said low voltage element may be moved relative to said high voltage element by rotation of the outside threaded member.

8. A high voltage variable condenser comprising a housing, a pair of capacitive elements carried by said housing, one of said elements being a high voltage element of tubular shape comprising an internal metal tube, said high voltage element being mounted upon one end of a compliant cantilever wire which extends axially within said element, said wire being rigidly fastened at the other end to a portion of said housing, a surrounding tubular body of ceramic material carried by said metal tube and an adherent layer consisting of a stable metal oxide overlaying said

ceramic material, the second element being a low voltage element comprising a metallic member having a tubular opening therein of a shape corresponding to said high voltage element, but slightly larger in size, whereby said high voltage element may slide axially within said opening, said opening having a surface formed of a layer of stable metal oxide and means carried by said housing for moving said elements relative to one another.

ROBERT P. GUTTERMAN.
